(57) **CLAIM**

The ornamental design for a belted cover for electronic device, as shown and described.

DESCRIPTION

FIG. 1 is a perspective view of a belted cover for electronic device showing the new design;

FIG. 2 is another perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right side elevational view thereof; and,

FIG. 8 is a left side elevational view thereof.

The broken lines illustrate unclaimed subject matter and form no part of the claimed invention.
